Application September 29, 1947, Serial No. 776,764

10 Claims. (Cl. 260—666)

1

This invention relates to the production of cyclohexane. The invention relates more particularly to a process for the production of cyclohexene of high purity from olefinic hydrocarbon mixtures comprising methylcyclopentane in admixture with close boiling hydrocarbons inseparable therefrom on a practical scale by fractionating means.

Cyclohexene is of value as the starting material for the production of a wide variety of valuable organic chemical derivatives which are themselves often important as intermediates in the manufacture of highly desirable products, such as, for example, the polyamide resins. Methods have been disclosed for the production of cyclohexene by processes comprising the intermediate production of a compound from which the desired cyclohexene could be produced with practical yields by available processes. Such processes are, however, not only cumbersome, but are generally relatively costly because of the nature of the individual chemical processing steps involved. A process enabling the efficient production of cyclohexene from readily available hydrocarbons is therefore particularly desirable. Processes, such as the process of U. S. Patent 2,385,555, bring within the realm of practicability the production of cyclohexene from cyclohexane. Such methods as disclosed heretofore, however, do not lend themselves to the practical scale production of cyclohexene of high purity from the unsaturated six carbon atom cyclic hydrocarbons, such as, for example, the methylcyclopentenes or methylcyclopentane, present in substantial amounts in readily available but highly complex hydrocarbon mixtures. Such readily available olefinic hydrocarbon mixtures comprise those obtained as products in the thermal or catalytic treatment of naturally occurring or synthetically produced hydrocarbons. Thus, the hydrocarbon mixtures boiling in the motor fuel boiling range obtained, for example, by the catalytic cracking of hydrocarbons, generally contain a substantial amount of methylcyclopentane and methylcyclopentenes. The complexity of these hydrocarbon mixtures and the presence therein of a multiplicity of hydrocarbons boiling at temperatures in close proximity to the boiling temperatures of methylcyclopentane or the methylcyclopentenes render extremely difficult and often impossible the separation therefrom of these cyclic hydrocarbons sufficiently free of close-boiling aliphatic hydrocarbons by methods available heretofore to enable their conversion to cyclohexene of relatively high purity. The complexity of operative

steps required, and in some cases the need for the use of catalysts or reagents of relatively high cost, to produce methylcyclopentane or methylcyclopentene of sufficient degree of purity for efficient conversion to cyclohexene by methods available heretofore, often render these processes highly impractical. The difficulty of separating methylcyclopentane or a single one of the methylcyclopentene isomers in relatively pure state from such hydrocarbon mixtures by methods available heretofore is rendered apparent by a realization of the multiplicity of hydrocarbons having closely approximating boiling temperatures generally present therein. Thus, a hydrocarbon fraction consisting essentially of hydrocarbons having six carbon atoms to the molecule and having a boiling range of 65° C. to 69° C., separated from an olefinic cracked gasoline by fractionation will generally contain 3-methylcyclopentene in admixture with the closely boiling hydrocarbons indicated in the following table:

Table A

	°C
2-ethylbutene-1	65
3-methylcyclopentene	67
2-methylpentene-2	67
3-methylpentene-2 (trans)	68
Hexene-3 (cis)	68
Hexene-3 (trans)	68
Hexene-2 (cis-and-trans)	68
n-Hexane	69

A fraction of such unsaturated cracked hydrocarbons boiling in the range of from 70° C. to 83° C. will generally contain methylcyclopentane, 4-methylcyclopentene and 1-methylcyclopentene in admixture with the close boiling six carbon atom hydrocarbons indicated in the following table:

Table B

	°C.
3-methylpentene-2 (cis)	71
Methylcyclopentane	72
2,3-dimethylbutene-2	73
4-methylcyclopentene	75
1-methylcyclopentene	76
Methylenecyclopentane	76
Benzene	80
Cyclohexane	81
Cyclohexene	83

Close boiling hydrocarbons other than the six carbon atom hydrocarbons are generally encountered which further complicates the problem of separation as evidenced from the following table of seven carbon atom aliphatic hydrocar-

bons boiling in the range of from 72° C. to 85° C. encountered in olefinic cracked gasolines:

Table C

	°C.
4,4-dimethylpentene-1	72
4,4-dimethylpentene-2	76
3,3-dimethylpentene-1	77
2,3,3-trimethylbutene-1	78
2,2-dimethylpentane	79
2,4-dimethylpentane	81
2,4-dimethylpentene-1	81
3,4-dimethylpentene-1	81
2,2,3-trimethylbutane	81
2,4-dimethylpentene-2	82
3-methylhexene-1	84
2,3-dimethylpentene-1	85
3-ethylpentene-1	85
4-methylhexene-2 (trans)	85

The relatively wide spread in boiling range of the three methylcyclopentene isomers and the fact that the practicality of a process for the production of relatively pure methylcyclopentenes is often dependent upon a recovery of at least the greater part of all three, render the use of processes involving such steps as fractionation and olefin extraction, as utilized heretofore, highly unsatisfactory.

In copending applications Serial No. 776,763, filed September 29, 1947, and Serial No. 776,765, filed September 29, 1947, processes are disclosed and claimed enabling the efficient production of methylcyclopentenes and cyclohexene in a high state of purity from the methylcyclopentene content of the complex hydrocarbon mixtures comprising them in admixture with close boiling open chain aliphatic hydrocarbons. The methylcyclopentane content of the charge, which generally constitutes an additional valuable source of unsaturated cyclic hydrocarbons is, however, not recovered as such, or as methylcyclopentene or cyclohexene free of close boiling open chain aliphatics, by these methods. Separation of a methylcyclopentane-containing fraction from such complex hydrocarbon mixtures and subjecting it directly to such a step as dehydrogenation will obviously result in the production of an unsaturated hydrocarbon mixture, the complexity of which often renders difficult, if not impossible, the efficient production of cyclohexene of high purity therefrom by methods available heretofore. Separation of the olefinic content of the methylcyclopentane fraction prior to the dehydrogenation step does not provide the solution to the problem since the resulting dehydrogenate, as a result of dehydrogenation of both cyclic and open chain saturates will again consist of a complex mixture of both cyclic and straight chain unsaturates of close boiling temperatures inseparable on a practical scale by fractionation.

It is an object of the present invention to provide an improved process for the more efficient production of cyclohexene from readily available complex methylcyclopentane-containing hydrocarbon mixtures comprising methylcyclopentane in admixture with close boiling aliphatic hydrocarbons inseparable therefrom on a practical scale by ordinary fractionating means.

Another object of the invention is the provision of an improved process for the more efficient production of cyclohexene of high purity from cracked olefinic gasolines.

Another object of the invention is the provision of an improved process for the more efficient production of cyclohexene of high purity

from olefinic hydrocarbon fractions comprising methylcyclopentane in admixture with close boiling aliphatic hydrocarbons. Other objects and advantages of the present invention will become apparent from the following detailed description thereof.

The objects and advantages of the present invention are obtained by fractionating a complex hydrocarbon mixture comprising methylcyclopentane in admixture with close boiling open chain aliphatic hydrocarbons from any suitable source, such as, for example, a cracked gasoline, to separate therefrom a methylcyclopentane-containing fraction. The methylcyclopentane fraction comprising the methylcyclopentane in admixture with close boiling open chain aliphatic hydrocarbons is subjected to catalytic hydrocarbon dehydrogenating conditions effecting the conversion of methylcyclopentane to methylcyclopentenes and the simultaneous conversion of at least a substantial part of the open chain saturated aliphatics present to open chain olefinic hydrocarbons. The products of dehydrogenation are fractionated to separate therefrom a lower boiling hydrocarbon fraction comprising 3-methylcyclopentene in admixture with close boiling aliphatic hydrocarbons having six carbon atoms to the molecule, and a higher boiling hydrocarbon fraction comprising 1-methylcyclopentene and 4-methylcyclopentene in admixture with close boiling aliphatic hydrocarbons having seven carbon atoms to the molecule. The lower boiling hydrocarbon fraction is subjected to olefin isomerizing conditions effecting the conversion of 3-methylcyclopentene to cyclic olefins comprising 1-methylcyclopentene and 4-methylcyclopentene in a first isomerizing zone. The higher boiling hydrocarbon fraction is separately subjected to olefin isomerizing conditions effecting the conversion of 1-methylcyclopentene and 4-methylcyclopentene to cyclic olefins comprising 3-methylcyclopentene in a second isomerizing zone. Methylcyclopentenes consisting essentially of 1- and 4-methylcyclopentenes are separated in a high state of purity from the effluence of the first isomerizing zone. Methylcyclopentenes consisting essentially of 3-methylcyclopentene in a high state of purity are separated from the effluence of the second isomerizing zone. The methylcyclopentenes thus separated from the effluence of the first and second isomerizing zones are combined and subjected to olefin isomerizing conditions in a third isomerizing zone effecting the conversion of methylcyclopentene to cyclohexene. Cyclohexene in a high state of purity is separated as a final product from the effluence of the third reaction zone.

The process of the invention is applied to the production of cyclohexene from complex hydrocarbon mixtures, comprising methylcyclopentane in admixture with close boiling aliphatic hydrocarbons, obtained from any suitable source. Thus, the charge to the system may comprise the methylcyclopentane-containing hydrocarbon mixtures obtained in the thermal or catalytic treatment of hydrocarbons, such as, for example, the methylcyclopentane-containing hydrocarbon mixtures obtained in the thermal and catalytic cracking, hydrogenation, destructive hydrogenation, isomerization, reforming, alkylation, and the like, of hydrocarbons. Other suitable starting materials comprise the products of hydrocarbon synthesis, the methylcyclopentane-containing hydrocarbon mixtures of natural occurrence, etc. In order to set forth more fully the nature of

the invention, it will be described herein with reference to the attached drawing wherein the single figure represents a more or less diagrammatical elevational view of one form of apparatus suitable for executing the process of the invention.

Referring to the drawing, a complex hydrocarbon mixture comprising methylcyclopentane in admixture with close boiling open chain aliphatic hydrocarbons, such as, for example, a cracked gasoline, taken from an outside source, is forced through line 10 into a feed fractionating zone. In the drawing the feed fractionating zone is represented by the single fractionator 11. It will be understood that in practical application of the invention a plurality of fractionators will generally be employed. In feed fractionator 11, the gasoline is fractionated to separate therefrom a hydrocarbon fraction comprising methylcyclopentane in admixture with close boiling open chain aliphatic hydrocarbons having six and seven carbon atoms to the molecule. Thus, the methylcyclopentane-containing fraction may have a boiling range of, for example, from about 68° C. to about 74° C. A fraction having a somewhat broader boiling range may be employed within the scope of the invention.

The methylcyclopentane-containing fraction is passed from feed fractionator 11 through valved line 14 into a suitable heating zone, such as, for example, an externally heated coil 15 positioned in a furnace structure 16. From coil 15 the heated methylcyclopentane-containing hydrocarbons are passed through line 17 into a dehydrogenation zone. The dehydrogenation zone may comprise a reaction chamber 18. Within reaction chamber 18 the methylcyclopentane-containing fraction is contacted with a suitable dehydrogenation catalyst, for example, a catalyst of the chrome-alumina type, such as a catalyst consisting essentially of an intimate mixture of oxides of chromium and aluminum, under hydrocarbon dehydrogenating conditions effecting the conversion of methylcyclopentane to methylcyclopentenes. The temperature within reactor 18 is maintained above about 500° C., for example, in the range of from about 450° C. to about 650° C., and preferably from about 500° C. to about 600° C. Temperature conditions within reaction chamber 18 are maintained by the heat input into the methylcyclopentane fraction flowing through coil 15. The dehydrogenation reaction is effected at atmospheric or superatmospheric pressures in the range of, for example, from about 1 to about 50 pounds absolute, and preferably from about 10 to about 20 pounds absolute. Higher pressures may, however, be employed. Contact times in the range of from about 0.2 second to about 5 seconds have been found suitable with a liquid hourly space velocity of from about 0.5 to 10. Although a chromium oxide-aluminum oxide catalyst is chosen in the illustrative description of the invention as the dehydrogenation catalyst employed in reaction chamber 18, the invention is in no wise limited to the use of this particular catalyst. Other suitable dehydrogenation catalysts comprise, for example, oxides of metals of groups V and VI of the periodic table. These materials are preferably employed in combination with suitable solid dispersing agents such as oxides of metals of groups II, III and IV of the periodic table, particularly oxides of aluminum, magnesium, zirconium; bauxite, clays, such as bentonites, montmorillonites, etc.; kieselguhr; crushed silica; glauconite sand; etc. Another suitable catalyst is activated carbon, alone or promoted with

oxides of metals of groups V and VI. Under these conditions methylcyclopentane will be converted to methylcyclopentenes essentially consisting of 1-methylcyclopentene, 3-methylcyclopentene and 4-methylcyclopentene within reaction chamber 18. Smaller amounts of methylcyclopentadiene and aromatics will also form. The open chain aliphatic hydrocarbons originally present in the methylcyclopentane fraction, such as the hexanes and some heptanes, will be converted, in part, to open chain olefinic hydrocarbons and aromatics. The following example is illustrative of the dehydrogenation of a methylcyclopentane-containing fraction in accordance with the process of the invention:

Example I

A methylcyclopentane concentrate separated by fractionation from a petroleum fraction is dehydrogenated by contact with a catalyst consisting of chromia-alumina containing 13.7% Cr, at a temperature of 550° C., atmospheric pressure and a liquid hourly space velocity of 2. A conversion of 23% is obtained. The converted material contains 36.9% mixed methylcyclopentenes. In a repetition of the operation under substantially identical conditions, but with the exception that hydrogen is added to the feed in a 1 to 1 mole ratio, the conversion of methylcyclopentane is 26% and the converted material contains 45.6% methylcyclopentenes.

The effluence emanating from reaction chamber 18, due to the presence of close boiling aliphatics originally present in the charge or formed during the dehydrogenation, will generally be of such complexity as to render exceedingly difficult, if not impossible, the separation therefrom of methylcyclopentenes free from open chain aliphatic hydrocarbons by such steps as fractionation as conducted on a practical scale. The complexity of the resulting mixture will furthermore render impractical the obtaining of cyclohexene of high purity therefrom by methods available heretofore. In accordance with the invention the effluence from reaction chamber 18 is therefore passed through line 20 provided with suitable cooling means, such as, for example, a heat exchanger 21, into a suitable dehydrogenation product separating zone.

In the drawing the dehydrogenation product separating zone is depicted by fractionators 22, 23 and 24. Within fractionator 22 a vapor fraction comprising hydrocarbons boiling below about 65° C. is separated as a vapor fraction from a liquid fraction comprising hydrocarbons boiling above about 65° C. The liquid fraction comprising isomeric methylcyclopentenes in admixture with close boiling aliphatic hydrocarbons and unconverted methylcyclopentane is passed from fractionator 22 by means of line 26 into fractionator 23. Within fractionator 23 a vapor fraction comprising 3-methylcyclopentene in admixture with close boiling hydrocarbons, such as, for example, a fraction boiling in the range of from about 66° C. to about 68° C., is separated as a vapor fraction from a liquid fraction comprising higher boiling hydrocarbons. The vapor fraction comprising 3-methylcyclopentene is taken overhead from fractionator 23 through line 28 and forms the charge to a first isomerizing zone.

The liquid fraction is passed from fractionator 23 through line 29 into fractionator 24. Within fractionator 24 a vapor fraction comprising unconverted methylcyclopentane, such as, for example, a fraction boiling in the range of from

about 68° C. to 74° C., is separated from a liquid fraction comprising 1-methylcyclopentene and 4-methylcyclopentene in admixture with close boiling aliphatic hydrocarbons, such as, for example, a fraction boiling in the range of from about 74° C. to about 77° C. The vapor fraction is recycled from fractionator 24 through line 30 into line 14. Before being introduced into line 14 it may be treated to remove diolefins or aromatics. The liquid fraction comprising 1-methylcyclopentene and 4-methylcyclopentene is taken from fractionator 24 by means of line 31 and forms the charge to a second and separate isomerizing zone of the process.

The 3-methylcyclopentene-containing fraction flowing through line 28 will comprise a plurality of open chain olefinic hydrocarbons having six carbon atoms to the molecule boiling at, or close to, the boiling temperature of 3-methylcyclopentene and therefore inseparable therefrom on a practical scale by such expedients as fractionation.

The 3-methylcyclopentene-containing fraction is passed from line 28 into a heating zone, such as, for example, an externally heated coil 33 positioned in a furnace structure 34. From heating coil 33, the heated 3-methylcyclopentene fraction is passed through line 35 into a suitable first isomerizing zone. The first isomerizing zone may comprise a reaction chamber 36.

A hydrocarbon fraction consisting essentially of 3-methylcyclopentene in admixture with close boiling aliphatic hydrocarbons may be introduced into line 28 from an outside source by means of valved line 38.

Within reaction chamber 36, the 3-methylcyclopentene fraction is contacted with an olefin isomerization catalyst at olefin isomerizing conditions set forth fully below, effecting the conversion of 3-methylcyclopentene to unsaturated cyclic olefins consisting essentially of 1-methylcyclopentene, 4-methylcyclopentene and a minor amount of cyclohexene. Under the isomerizing conditions maintained in reactor 36 at least a substantial part of the six carbon atom open chain olefins are simultaneously converted to isomeric open chain olefins boiling below 66° C. Isomerization of the 3-methylcyclopentene fraction under these conditions is illustrated by the following example:

Example II

An olefinic hydrocarbon fraction having a boiling range of from about 66° C. to about 68° C., separated from a catalytically cracked gasoline by fractionation, and having a 3-methylcyclopentene content of 40% and an open chain C₆ olefin content of 55% is contacted with a bauxite catalyst at a temperature of 275° C. and a pressure of 15 pounds absolute. A conversion of 3-methylcyclopentene to 1-methylcyclopentene and 4-methylcyclopentene of 70%, and of open chain olefins to olefins boiling below 66° C. of 30% is obtained. Only about 0.5% of the 3-methylcyclopentene is converted to cyclohexene.

Effluence from reactor 36 comprising 1-methylcyclopentene, 4-methylcyclopentene, unconverted 3-methylcyclopentene, some cyclohexene, and the open chain isomerized and unisomerized six carbon atom olefins is passed through line 39, provided with suitable cooling means, such as, for example, a heat exchanger 40, into a product separating zone. Since the highest boiling non-cyclic C₆ olefin boils at 73° C., and 1-methylcyclopentene, 4-methylcyclopentene and cyclo-

hexene boil at 75° C., 76° C. and 83° C., respectively, the 1- and 4-methylcyclopentenes along with the cyclohexene are readily separated from the reactor effluence by fractionation.

The product separating zone receiving reaction products from line 39 is depicted in the drawing by fractionators 41 and 42. Within fractionator 41 a vapor fraction comprising isomerized open chain olefins boiling below 60° C. is separated from a liquid fraction comprising hydrocarbons boiling above 66° C. The liquid fraction is passed from fractionator 41 through line 44 into fractionator 42. Within fractionator 42 hydrocarbons comprising 1-methylcyclopentene and 4-methylcyclopentene are separated as a liquid fraction from a vapor fraction having a boiling range of about 66° C. to about 74° C. comprising unconverted 3-methylcyclopentene in admixture with close boiling aliphatic olefins. At least a part of the vapor fraction is recycled from fractionator 42, through line 45, into line 28. Valved line 46 is provided to enable the bleeding of a portion of the recycle stream from the system to avoid the accumulation of saturated hydrocarbons boiling in the boiling range of the recycled stream. Although such bleeding will generally suffice, a portion or all of the recycle stream may be by-passed through suitable saturated hydrocarbon-removing means, such as, for example, an extraction zone not shown in the drawing. The liquid fraction comprising 1- and 4-methylcyclopentene and cyclohexene is taken from fractionator 42 through valved line 48.

The hydrocarbon fraction comprising 1-methylcyclopentene and 4-methylcyclopentene separated from the dehydrogenation products, passing through line 31, will often comprise close boiling heptenes inseparable from these methylcyclopentene isomers by ordinary fractionating means, as well as some benzene, toluene, and other higher boiling hydrocarbons. The amount of heptenes present will generally be dependent upon the range of the methylcyclopentane fraction passed to the reaction chamber 18. Due to the complexity of composition of the fraction when substantial amounts of such open chain aliphatics are present, it does not lend itself to treatment for the direct conversion of the methylcyclopentene content thereof to cyclohexene of high purity on a practical scale. In accordance with the invention when the hydrocarbon stream flowing through line 31 comprises substantial amounts of open chain aliphatics, it is passed into a heating zone, such as, for example, an externally heated coil 53, positioned in a furnace structure 54. From coil 53 the heated hydrocarbon stream is passed through line 55 to a second isomerizing zone of the process, such as, for example, a reaction chamber 56.

Additional hydrocarbons from an outside source consisting essentially of 1- and 4-methylcyclopentenes in admixture with close boiling open chain olefins having seven carbon atoms to the molecule may be introduced into the system by means of valved line 58.

Within reactor 56 the hydrocarbon stream is contacted with an olefin isomerizing catalyst at olefin isomerizing conditions effecting the conversion of 1-methylcyclopentene and 4-methylcyclopentene to cyclic olefins consisting essentially of 3-methylcyclopentene and some cyclohexene.

Effluence from reactor 56 is passed through line 60, provided with suitable cooling means, such as, for example, a heat exchanger 61, into a product separating zone. The product separating zone re-

ceiving effluence from reactor 56 is depicted in the drawing by fractionators 62 and 63.

Since the boiling temperature of 3-methylcyclopentene is 67° C. and that of the lowest boiling heptene is 72° C., separation of the 3-methylcyclopentene from the reactor effluence is now easily accomplished by conventional fractionating means. Within fractionator 62 a vapor fraction comprising 3-methylcyclopentene is separated from liquid fraction comprising unconverted 1- and 4-methylcyclopentenes in admixture with close boiling heptenes and some cyclohexene. The vapor fraction consisting of 3-methylcyclopentene is taken overhead from fractionator 62 through line 64.

The liquid fraction is passed from fractionator 62 through line 67 into fractionator 63. Within fractionator 63 a vapor fraction comprising unconverted 1- and 4-methylcyclopentenes in admixture with close boiling heptenes and cyclohexene, such as, for example, a fraction boiling in the range of about 70° C. to 84° C., is separated as a vapor fraction from a liquid fraction boiling above about 84° C. comprising higher boiling materials including isomeric open chain C₇ olefins formed within the system. The liquid fraction is taken from fractionator 63 through valved line 68 and eliminated from the system. The vapor fraction is recycled from fractionator 63 by means of line 69 into line 31. A valved line 10 is provided for the bleeding of a part of the recycle stream from the system to avoid the accumulation of open chain or aromatic hydrocarbons.

The manner of isomerization of the 1- and 4-methylcyclopentene-containing fraction to products comprising 3-methylcyclopentene in accordance with the process of the invention is illustrated by the following example:

Example III

An olefinic hydrocarbon fraction, separated by fractionation from a catalytically cracked gasoline, boiling in the range of 74° C. to 77° C., having a 1- and 4-methylcyclopentene content of 70% and a heptene content of 25% is isomerized by contact with a bauxite catalyst at 275° C., pressure of 15 pounds absolute, and a liquid hourly space velocity of 7. A conversion of 1- and 4-methylcyclopentene to 3-methylcyclopentene of 30% is obtained.

The methylcyclopentenes flowing through line 48 consisting essentially of 1- and 4-methylcyclopentenes, and the methylcyclopentenes flowing through line 64 consisting essentially of 3-methylcyclopentene, both of which streams are now free of any substantial amount of open chain aliphatic hydrocarbons, are passed through lines 72 and 73, respectively, discharging into line 74 leading to a suitable heating zone, such as, for example, an externally heated coil 15, positioned in a furnace structure 76. From coil 76 the heated methylcyclopentenes are passed through line 77 into a third isomerizing zone. The third isomerizing zone may comprise a reaction chamber 78. Within reaction chamber 78 the methylcyclopentenes are subjected to olefin isomerizing conditions effecting the conversion of methylcyclopentenes to cyclohexene. Effluence from reaction chamber 78 comprising cyclohexene and unconverted methylcyclopentenes is passed through line 81, provided with suitable cooling means, such as a heat exchanger 82, into fractionator 83. Unconverted 1-, 3- and 4-methylcyclopentenes are separated as a vapor fraction from a liquid fraction comprising cyclohexene within

fractionator 83. The vapor fraction is recycled from fractionator 83 through line 85 into line 72. The liquid fraction consisting essentially of cyclohexene is passed from fractionator 83 through line 86 into a fractionator 87. Within fractionator 87 a vapor fraction consisting essentially of cyclohexene in a high state of purity is separated from a liquid fraction comprising any hydrocarbons higher boiling than cyclohexene which may have been formed. The vapor fraction comprising cyclohexene is taken from fractionator 87 through valved line 88 as the final product. The liquid fraction is taken from fractionator 87 through valved line 89 and eliminated from the system. It is to be pointed out that, generally, but a relatively small amount of hydrocarbons higher boiling than cyclohexene are produced within the system.

The following example is illustrative of the conversion of the mixed methylcyclopentenes, free of any substantial amount of open chain aliphatics, to unsaturated cyclic olefins consisting essentially of cyclohexene:

Example IV

A mixture of 1-, 3- and 4-methylcyclopentenes is isomerized over a catalyst consisting of adsorptive alumina that has been treated with dilute aqueous hydrochloric acid, washed, dried and calcined at 700° C. The isomerization effected at 500° C. and atmospheric pressure with a liquid hourly space velocity of 15. The conversion to cyclohexenes is 14% per pass.

If desired, at least a substantial part of the olefinic content of the methylcyclopentane stream flowing through line 14 may be removed prior to introduction of the stream into heating coil 15 by passage through suitable olefine-removing means. Thus, the methylcyclopentane fraction may be by-passed from line 14, through line 95, into a suitable extraction zone comprising an extraction column 96 and a stripping column 97. Within column 96 the hydrocarbon stream is contacted with a countercurrent flow of a medium having a preferential solvent action for olefins. The remaining saturated hydrocarbon stream comprising methylcyclopentane and close boiling open chain saturated hydrocarbons, such as hexanes, is passed from extraction column 96 through line 98 into line 14 leading to coil 15. When thus removing the olefinic content from the methylcyclopentane fraction passing to coil 15 the dehydrogenation products generally will be free of any substantial amount of seven carbon atom open chain aliphatic hydrocarbons. The methylcyclopentenes consisting essentially of 1- and 4-methylcyclopentenes taken from fractionator 24 through line 31 accordingly will be substantially free of close boiling open chain hydrocarbons and may be passed directly into line 14. The 3-methylcyclopentenes in the dehydrogenation product will, however, still be admixed with substantial amounts of close boiling open chain aliphatic hydrocarbons, such as, for example, hexenes, due to the presence in the methylcyclopentane stream passing to coil 15 of saturated open chain hydrocarbons having six carbon atoms to the molecule. The 3-methylcyclopentene fraction separated from the dehydrogenation products in fractionator 23 as a vapor fraction is therefore passed to the first isomerizing zone notwithstanding the removal of the olefinic content of the methylcyclopentane fraction flowing through line 14.

Catalysts employed in reaction chambers 36, 56 and 78 comprise any olefin isomerizing catalyst

11

of the solid type. Suitable olefin isomerizing catalysts comprise, for example, the naturally occurring or synthetically prepared solid adsorptive aluminous materials, such as the aluminum oxides, activated alumina, bauxite, silica-alumina, etc. These catalytic materials may be subjected to a pretreatment before use. Such pretreatments comprise, for example, subjection to elevated temperatures, optionally in the presence of gaseous materials such as hydrogen, nitrogen, steam, gases comprising them or the catalysts may be contacted with an inorganic mineral acid such as hydrochloric acid, sulfuric acid, carbamic acid, hydrofluoric acid, boric acid, etc. A particularly preferred type of catalyst comprises adsorptive aluminous materials containing substantial amounts of gamma alumina which has been pretreated with an acidic material. Although adsorptive materials are preferred as catalysts for the isomerization of the methylcyclopentenes, the invention is not necessarily limited thereto and other catalysts capable of activating the olefin isomerization reaction may be employed. Such catalysts comprise, for example, catalysts of the type of naturally occurring siliceous materials such as clays, bentonites, or the like, alumina-silica compounds or mixtures thereof, zeolites, oxides of Be, Si, Ti, Th, V, Zr, Mn, etc. Other suitable catalysts are those comprising phosphoric acid and silica, as well as any acid of low volatality, preferably on a solid oxide support material. Of the isomerization catalysts, those consisting essentially of alumina in combination with silica are somewhat preferred.

Temperatures within reactors 36, 56 and 78 are maintained in the range of from about 150° C. to about 650° C., and preferably from about 200° C. to 550° C. Temperature conditions in reactors 36, 56 and 78 are controlled by the heat input into the hydrocarbon streams flowing through externally heated coils 33, 53 and 75, respectively. The isomerization reactions are preferably executed in the vapor phase. Atmospheric or superatmospheric pressures may be maintained within reactors 33, 53 and 75. Pressures close to atmospheric have been found satisfactory. Throughput rates in terms of a liquid hourly space velocity in the range of, for example, from about 0.5 to about 25 are employed.

Although substantially identical conditions of temperature and throughput rate ranges as well as the same types of catalyst may be employed in all three of the olefin isomerizing zones of the process, within the scope of the invention, in a preferred modification milder olefin isomerizing conditions are maintained in reaction chambers 36 and 56 than in reaction chamber 78. Thus, in the modification of the invention, an isomerization catalyst selected from the group consisting of silica-phosphoric acid type catalysts, activated alumina, or bauxite is employed in reaction chambers 36 and 56, while a catalyst such as, for example, a catalyst consisting essentially of acid-treated adsorptive alumina, or alumina in combination with silica, is employed in reaction chamber 78. Milder isomerization conditions within reaction chambers 36 and 56 may also be obtained by maintaining therein temperatures within the lower range of the prescribed suitable operating range, such as, for example, a temperature in the range of from about 150° C. to about 350° C., while the higher temperatures in the prescribed broad temperature range, such as, for example, a temperature of from about 400° C. to

12

about 550° C., are maintained within reaction chamber 78.

Under the above-defined conditions 3-methylcyclopentene is converted to cyclic olefins consisting predominantly of 1- and 4-methylcyclopentenes in reactor 36; 1- and 4-methylcyclopentenes are converted to cyclic olefins consisting essentially of 3-methylcyclopentene in reactor 56; and 1-, 3- and 4-methylcyclopentenes are converted to cyclohexene in reactor 78.

For the purpose of clarity, all parts of apparatus not essential to a complete description of the invention comprising, for example, pumps, condensers, complete fractionating systems, accumulators, etc., have been omitted from the drawing. It is to be understood that the apparatus shown may be modified as apparent to one skilled in the art without departing from the scope of the invention.

The claimed invention is:

1. The process for the production of cyclohexene in a relatively high state of purity from a hydrocarbon fraction consisting essentially of methylcyclopentane in admixture with close boiling open chain hydrocarbons, which comprises contacting said methylcyclopentane fraction with a dehydrogenating catalyst under dehydrogenating conditions converting methylcyclopentane to methylcyclopentene in a dehydrogenating zone, fractionating from the effluence of the dehydrogenating zone a lower boiling fraction comprising 3-methylcyclopentene in admixture with close boiling open chain hydrocarbons and a higher boiling fraction comprising 1-methylcyclopentene and 4-methylcyclopentene in admixture with close boiling open chain hydrocarbons, contacting said lower boiling fraction with a solid adsorptive aluminous material under isomerizing conditions effecting the conversion of 3-methylcyclopentene to 1-methylcyclopentene and 4-methylcyclopentene in a first isomerizing zone, fractionating 1-methylcyclopentene and 4-methylcyclopentene free of any substantial amount of open chain hydrocarbons from the effluence of the first isomerizing zone, contacting said higher boiling fraction with a solid adsorptive aluminous material under isomerizing conditions effecting the conversion of 1-methylcyclopentene and 4-methylcyclopentene to 3-methylcyclopentene in a second isomerizing zone, fractionating 3-methylcyclopentene free of any substantial amount of open chain hydrocarbons from the effluence of the second isomerizing zone, contacting said 1-methylcyclopentene and 4-methylcyclopentene separated from the effluence of said first isomerizing zone together with the 3-methylcyclopentene separated from the effluence of the second isomerizing zone with a solid adsorptive aluminous material under isomerizing conditions effecting the conversion of methylcyclopentenes to cyclohexene in a third isomerizing zone, and fractionating cyclohexene in a high state of purity from the effluence of said third isomerizing zone.

2. The process for the production of cyclohexene in a relatively high state of purity from a hydrocarbon fraction consisting essentially of methylcyclopentane in admixture with close boiling open chain aliphatic hydrocarbons, which comprises contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a lower boiling fraction comprising 3-methylcyclopentene in

admixture with close boiling open chain hydrocarbons and a higher boiling fraction comprising 1-methylcyclopentene and 4-methylcyclopentene in admixture with close boiling open chain hydrocarbons, contacting said lower boiling fraction with a catalyst consisting essentially of adsorptive alumina under isomerizing conditions effecting the conversion of 3-methylcyclopentene to 1-methylcyclopentene and 4-methylcyclopentene in a first isomerizing zone, fractionating 1-methylcyclopentene and 4-methylcyclopentene free of any substantial amount of open chain hydrocarbons from the effluence of the first isomerizing zone, contacting said higher boiling fraction with a catalyst consisting essentially of adsorptive alumina under isomerizing conditions effecting the conversion of 1-methylcyclopentene and 4-methylcyclopentene to 3-methylcyclopentene in a second isomerizing zone, fractionating 3-methylcyclopentene free of any substantial amount of open chain hydrocarbons from the effluence of the second isomerizing zone, contacting said 1-methylcyclopentene and 4-methylcyclopentene separated from the effluence of said first isomerizing zone together with the 3-methylcyclopentene separated from the effluence of the second isomerizing zone with a catalyst consisting essentially of adsorptive alumina in combination with silica under isomerizing conditions effecting the conversion of methylcyclopentenes to cyclohexene in a third isomerizing zone, and fractionating cyclohexene in a high state of purity from the effluence of said third isomerizing zone.

3. The process for the production of cyclohexene in a relatively high state of purity from a hydrocarbon fraction consisting essentially of methylcyclopentene in admixture with close boiling open chain aliphatic hydrocarbons, which comprises contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a lower boiling fraction comprising 3-methylcyclopentene in admixture with close boiling open chain hydrocarbons and a higher boiling fraction comprising 1-methylcyclopentene and 4-methylcyclopentene in admixture with close boiling open chain hydrocarbons, contacting said lower boiling fraction with a solid olefin isomerizing catalyst under isomerizing conditions effecting the conversion of 3-methylcyclopentene to 1-methylcyclopentene and 4-methylcyclopentene in a first isomerizing zone, fractionating 1-methylcyclopentene and 4-methylcyclopentene free of any substantial amount of open chain hydrocarbons from the effluence of the first isomerizing zone, contacting said higher boiling fraction with a solid olefin isomerizing catalyst under isomerizing conditions effecting the conversion of 1-methylcyclopentene and 4-methylcyclopentene to 3-methylcyclopentene in a second isomerizing zone, fractionating 3-methylcyclopentene free of any substantial amount of open chain hydrocarbons from the effluence of the second isomerizing zone, contacting said 1-methylcyclopentene and 4-methylcyclopentene separated from the effluence of said first isomerizing zone together with the 3-methylcyclopentene separated from the effluence of the second isomerizing zone with a solid olefin isomerizing catalyst under isomerizing conditions effecting the conversion of methylcyclopentenes to cyclohexene in a third isomerizing zone, and fractionating cyclohexene in a high state of purity from the effluence of said third isomerizing zone.

ity from the effluence of said third isomerizing zone.

4. The process for the production of cyclohexene in a relatively high state of purity from cracked gasoline comprising methylcyclopentane in admixture with close boiling open chain aliphatic hydrocarbons, which comprises fractionating a methylcyclopentane fraction boiling in the range of from about 68° C. to about 74° C. from said gasoline, contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a lower boiling fraction boiling in the range of from about 66° C. to about 68° C. comprising 3-methylcyclopentene in admixture with close boiling open chain hydrocarbons and a higher boiling fraction having a boiling range of from about 74° C. to about 77° C. comprising 1-methylcyclopentene and 4-methylcyclopentene in admixture with close boiling open chain hydrocarbons, contacting said lower boiling fraction with a solid olefin isomerizing catalyst under isomerizing conditions effecting the conversion of 3-methylcyclopentene to 1-methylcyclopentene and 4-methylcyclopentene in a first isomerizing zone, fractionating 1-methylcyclopentene and 4-methylcyclopentene free of any substantial amount of open chain hydrocarbons from the effluence of the first isomerizing zone, contacting said higher boiling fraction with a solid olefin isomerizing catalyst under isomerizing conditions effecting the conversion of 1-methylcyclopentene and 4-methylcyclopentene to 3-methylcyclopentene in a second isomerizing zone, fractionating 3-methylcyclopentene free of any substantial amount of open chain hydrocarbons from the effluence of the second isomerizing zone, contacting said 1-methylcyclopentene and 4-methylcyclopentene separated from the effluence of said first isomerizing zone together with the 3-methylcyclopentene separated from the effluence of the second isomerizing zone with a solid olefin isomerizing catalyst under isomerizing conditions effecting the conversion of methylcyclopentenes to cyclohexene in a third isomerizing zone, and fractionating cyclohexene in a high state of purity from the effluence of said third isomerizing zone.

5. The process for the production of cyclohexene in a high state of purity from a hydrocarbon fraction consisting essentially of methylcyclopentane in admixture with close boiling open chain aliphatic hydrocarbons, which comprises contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a fraction comprising 3-methylcyclopentene in admixture with close boiling open chain hydrocarbons, contacting said 3-methylcyclopentene fraction with a solid aluminous material under isomerizing conditions effecting the conversion of 3-methylcyclopentene to 1-methylcyclopentene and 4-methylcyclopentene in a first isomerizing zone, fractionating methylcyclopentenes consisting essentially of 1-methylcyclopentene and 4-methylcyclopentene free of any substantial amount of open chain aliphatic hydrocarbons from the effluence of said first isomerizing zone, contacting said methylcyclopentenes fractionated from the effluence of said first isomerizing zone with a solid aluminous material

15

under isomerizing conditions effecting the conversion of methylcyclopentenes to cyclohexene in a second isomerizing zone, and fractionating cyclohexene in a relatively high state of purity from the effluent of said second isomerizing zone.

6. The process for the production of cyclohexene in a high state of purity from a cracked gasoline fraction consisting essentially of methylcyclopentane in admixture with close boiling open chain aliphatic hydrocarbons, which comprises contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a fraction comprising 3-methylcyclopentene in admixture with close boiling open chain hydrocarbons, contacting said 3-methylcyclopentene fraction with a catalyst consisting essentially of adsorptive alumina under isomerizing conditions effecting the conversion of 3-methylcyclopentene to 1-methylcyclopentene and 4-methylcyclopentene in a first isomerizing zone, fractionating methylcyclopentenes consisting essentially of 1-methylcyclopentene and 4-methylcyclopentene free of any substantial amount of open chain hydrocarbons from the effluence of said first isomerizing zone, contacting said methylcyclopentenes fractionated from the effluence of said first isomerizing zone with a catalyst consisting essentially of alumina in combination with silica under isomerizing conditions effecting the conversion of methylcyclopentenes to cyclohexene in a second isomerizing zone, and separating cyclohexene in a relatively high state of purity from the effluence of said second isomerizing zone.

7. The process for the production of cyclohexene in a high state of purity from a hydrocarbon fraction consisting essentially of methylcyclopentane in admixture with close boiling open chain aliphatic hydrocarbons, which comprises contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a fraction comprising 3-methylcyclopentene in admixture with close boiling open chain aliphatic hydrocarbons, contacting said 3-methylcyclopentene-containing fraction with a solid olefin isomerizing catalyst under isomerizing conditions effecting the conversion of 3-methylcyclopentene to 1-methylcyclopentene and 4-methylcyclopentene in a first isomerizing zone, fractionating methylcyclopentenes consisting essentially of 1-methylcyclopentene and 4-methylcyclopentene free of any substantial amount of open chain aliphatic hydrocarbons from the effluence of said first isomerizing zone, contacting said methylcyclopentenes fractionated from the effluence of said first isomerizing zone with a solid olefin isomerizing catalyst under isomerizing conditions effecting the conversion of methylcyclopentenes to cyclohexene in a second isomerizing zone, and separating cyclohexene in a relatively high state of purity from the effluence of said second isomerizing zone.

8. The process for the production of cyclohexene in a high state of purity from a hydrocarbon fraction consisting essentially of methylcyclopentane in admixture with close boiling open chain aliphatic hydrocarbons, which comprises

16

contacting said methylcyclopentane fraction with a dehydrogenating catalyst under dehydrogenating conditions converting methylcyclopentane to methylcyclopentenes in a dehydrogenating zone, 5 fractionating from the effluence of the dehydrogenating zone a fraction comprising 1-methylcyclopentene and 4-methylcyclopentene in admixture with close boiling open chain hydrocarbons, contacting said 1- and 4-methylcyclopentene fraction with a catalyst consisting essentially 10 of adsorptive alumina under isomerizing conditions effecting the conversion of 1-methylcyclopentene and 4-methylcyclopentene to 3-methylcyclopentene in a first isomerizing zone, 15 fractionating 3-methylcyclopentene free of any substantial amount of open chain aliphatic hydrocarbons from the effluence of said first isomerizing zone, contacting said 3-methylcyclopentene separated from the effluence of said first 20 isomerizing zone with a catalyst consisting essentially of adsorptive alumina under isomerizing conditions effecting the conversion of methylcyclopentenes to cyclohexene in a second isomerizing zone, and fractionating cyclohexene in a relatively high state of purity from the effluence of 25 said second isomerizing zone.

9. The process for the production of cyclohexene in a high state of purity from a cracked gasoline fraction consisting essentially of methylcyclopentane in admixture with close boiling open chain aliphatic hydrocarbons, which comprises contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a fraction comprising 1-methylcyclopentene and 4-methylcyclopentene in admixture with close boiling open chain hydrocarbons, contacting said 1- and 4-methylcyclopentene fraction with a catalyst consisting essentially of adsorptive alumina under isomerizing conditions effecting the conversion of 1-methylcyclopentene and 4-methylcyclopentene to 3-methylcyclopentene in a first isomerizing zone, fractionating 3-methylcyclopentene free of any substantial amount of open chain aliphatic hydrocarbons from the effluence of said first isomerizing zone, contacting said 3-methylcyclopentene separated from the effluence of said first isomerizing zone with a catalyst consisting essentially of alumina in combination with silica under isomerizing conditions effecting the conversion of methylcyclopentenes to cyclohexene in a second isomerizing zone, and separating cyclohexene in a relatively high state of purity from the effluence of said second isomerizing zone.

10. The process for the production of cyclohexene in a high state of purity from a hydrocarbon fraction consisting essentially of methylcyclopentane in admixture with close boiling open chain aliphatic hydrocarbons, which comprises contacting said methylcyclopentane fraction with a dehydrogenating catalyst under dehydrogenating conditions converting methylcyclopentane to methylcyclopentenes in a dehydrogenating zone, fractionating from the effluence of the dehydrogenating zone a fraction comprising 1-methylcyclopentene and 4-methylcyclopentene in admixture with close boiling open chain hydrocarbons, contacting said 1- and 4-methylcyclopentene fraction with a solid olefin isomerizing catalyst under isomerizing conditions effecting the conversion of 1-methylcyclopentene and 4-methylcyclopentene to 3-methylcyclopentene in a first isomerizing zone, fractionating 3-methylcyclop-

17

pentene free of any substantial amount of open chain aliphatic hydrocarbons from the effluence of said first isomerizing zone, contacting said 3-methylcyclopentene separated from the effluence of said first isomerizing zone with a solid olefin isomerizing catalyst under isomerizing conditions effecting the conversion of methylcyclopentenes to cyclohexene in a second isomerizing zone, and separating cyclohexene in a relatively high state of purity from the effluence of said second isomerizing zone.

HERVEY H. VOGE,
GEORGE M. GOOD.
